[57] CLAIM

The ornamental design for a bush cutter, as shown and described.

DESCRIPTION

FIG. 1 is a perspective view of a bush cutter showing my new design;

FIG. 2 is a right side elevational view thereof;

FIG. 3 is a bottom view thereof;

FIG. 4 is a rear elevational view thereof;

FIG. 5 is a front elevational view thereof;

FIG. 6 is a left side elevational view thereof; and,

FIG. 7 is a top plan view thereof.

The contrasting stippled shading on the handle represents a roughened gripping surface.
